(57) **CLAIM**

I claim the ornamental design for an integrated USB extension cord, as shown and described.

DESCRIPTION

FIG. 1 is a perspective view of the first embodiment of an integrated USB extension cord;

FIG. 2 is a top view of the first embodiment;

FIG. 3 is a bottom view of the first embodiment;

FIG. 4 is a left-side view of the first embodiment;

FIG. 5 is a right-side view of the first embodiment;

FIG. 6 is a front view of the first embodiment;

FIG. 7 is a back view of the first embodiment;

FIG. 8 is a perspective view of the second embodiment of an integrated USB extension cord;

FIG. 9 is top view of the second embodiment;

FIG. 10 is bottom view of the second embodiment;

FIG. 11 is a left-side view of the second embodiment;

FIG. 12 is a right-side view of the second embodiment;

FIG. 13 is a front view of the second embodiment;

FIG. 14 is a back view of the second embodiment;

FIG. 15 is a perspective view of the third embodiment of an integrated USB extension cord;

FIG. 16 is a top view of the third embodiment;

FIG. 17 is a bottom view of the third embodiment;

FIG. 18 is a left-side view of the third embodiment;

FIG. 19 is a right-side view of the third embodiment;

FIG. 20 is a front view of the third embodiment; and,

FIG. 21 is a back view of the third embodiment.

The broken lines showing specific USB ports are included for the purpose of illustrating environmental structure and form no part of the claimed design.

1 Claim, 18 Drawing Sheets
